EARTH ANCHOR

Clarence W. Brakensiek, St. Louis, Mo.

Application February 23, 1937, Serial No. 126,978

6 Claims. (Cl. 189—92)

This invention relates to improvements in earth anchors, and more particularly to those of so-called expanding type, wherein a central body serves to carry a plurality of pivotally mounted blades or vanes.

The general objects of the invention are attained in an anchor of the type noted, having a stronger, more effective arrangement and design of blades, and one in which the blade elements and body are so arranged as to minimize driving effort, and in case of installation in a pre-bored hole, such as to require an opening or passage of reduced size.

Yet another object of the invention is attained in an improved design of blade and blade mounting in an expanding type of anchor, the blade arrangement embodying an improved pivotal connection between each of the blades and the body of the anchor.

Still another object of the invention is attained in an improved construction and arrangement of body and blades providing anti-spiralling provisions, tending to minimize rotational tendencies of the anchor while being driven and when located in final driven position.

A further object of the invention is attained in certain improvements in the shape of the blades for anchors of the type noted, in a manner to enhance the opening of the blades responsively to a slight upward pull on the anchor at the time of its original setting.

The foregoing and many other objects will clearly appear from the following detailed description of a presently preferred embodiment, considered in connection with the accompanying drawing, in which:

Fig. 1 is a top view of the improved anchor with the blades in unexpanded position, as it appears prior to setting; Fig. 2 is a side elevation of the anchor shown by Fig. 1; Fig. 3 is a bottom plan view of the anchor of Figs. 1 and 2, looking upwardly along its axis; Figs. 4 and 5 are sectional elevations taken respectively, along lines 4—4 and 5—5 of Fig. 2; Fig. 6 is a section taken transversely through the rear or heel portion of one of the blades or vanes, along line 6—6 of Fig. 2; Fig. 7 is a somewhat reduced side elevation of the anchor as it appears in expanded form, Fig. 8 is a fragmentary vertical section through the upper portion of the anchor body, illustrating a manner of securing a cable to the anchor, and Fig. 9 is a side elevation, partly in section, on a reduced scale, illustrating a slightly modified form of anchor.

Referring now by characters of reference to

the drawing, the anchor body includes a pilot or point portion 10 characterized according to present preference by nine triangular facets or faces resulting from the provision of three projections 11, each pair of which defines therebetween a channel 12 extending upwardly from the point proper, 13. In driving the anchor or in setting it in a prebored hole, the channels 12 serve to engage the surrounding earth in a manner tending to prevent rotation of the anchor about its axis, the resultant shape of the point or pilot of the body constituting anti-spiralling provisions or means. It will be noted that each of the outermost faces 11 of the point increases in width from the lower tip or point of the anchor, up to the terminus of the pilot portion, and that the width of each of these outer faces at its upper end, appreciably exceeds the width of an adjacent pivot structure for the flukes or vanes, hereinafter to be described. From this it results that as the anchor is being driven, any stones or hard objects encountered by the point of the anchor are deflected to a position laterally of the blade pivots, so that the pivots and heel parts of the blades are thus materially protected from damage during driving.

From the pilot portion 10 the body extends upwardly into a neck portion 14, and upwardly of the neck is a socket structure 15, the socket of which is tapped as at 16, for the threaded reception of an anchor rod 17. The rod is or may be of conventional form, and of suitable length, being usually provided at its outer or free end with a cable eye or the like (not shown). Projecting laterally of the upper portion of the socket-forming part 15, is a plurality, shown as 3, of ears or lugs 18, the outer faces of which are coplanar with the outer surface of the socket-forming part 15. The projections 18 serve, in driving or setting the anchor, as abutments to be engaged by the lower terminus of a tube or a special driving tool through which axial pressure is imparted to the anchor in driving. It will appear also that the projections 18, being located respectively to the rear and centrally of the several blades or vanes, serve as stops therefor, limiting the retracting pivotal movement of the vanes to the positions shown by Figs. 1, 2 and 4.

From the foregoing description of the body portion it will appear that it exhibits an improvement in economy of metal, consistent with provisions for the requisite thickness or body of metal in those zones subjected to the greatest stresses, both in driving and in service.

The neck portion 14 is provided with branches

or arms 20, which project horizontally from the body, and just above the pilot portion 10. These projections are each apertured as at 21 for the reception of a pivot pin 22, each of such pins serving as a hinge or pivot connection between the body and one of the vanes, hereinafter described in detail and indicated generally at 23.

A point of novelty is involved in the manner of securing the pins against axial displacement, after assembly of the several vanes 23 to the body. For this purpose there is provided on each of the pins a milled or knurled portion 25, preferably in the type of anchor shown, being the central or intermediate area of the pin, and this milled area on the pin is of increasing depth from one end of the area to the other. By further preference, one end of each of the pins 22 is beveled as at 26 (Fig. 5) to facilitate in assembly, starting of the pin through the openings therefor in the vanes 23 and in the arms 20. The relation of diameters of the milled portions 25 and the openings 21 is such that the pins, upon being firmly driven or pressed into place, undergo a deformation of the milled portions, with the effect of attaining a positive frictional securing of the pins against axial displacement and in nonrotative relation within the arms 20. This manner of assembly obviates the threading of the pins and the provision of holding nuts, cotter keys or any of the other usual provisions for retaining pins or pivots against axial displacement and possible loss while setting the anchor and after it is in use.

In lieu of the use of an anchor rod 17, it may be desirable in certain installations to engage the anchor with a stranded cable or other flexible tension element, as indicated at 27. As a convenient means of securing of such a cable to the body of the anchor, the socket-forming portion 15 is provided with a plurality, shown as 3, of branched openings 28. By dividing the strands 40 of the cable and distributing the strands beyond the socket through the several openings 28, thereafter sweating the cable firmly into place as by a body of poured metal 29, the cable is firmly secured to the body. In case the anchor is provided with a tension element such as a cable, thus obviating entirely the use of a rod, it is greatly preferred that the cable be formed of some corrosion-resisting metal, such as stainless steel. This material has been found to resist rusting and any ordinary chemical effects due to acid or alkaline soils, to a remarkable degree. It thus becomes possible by reason of the increased availability of cable formed of stainless steel or some equivalent corrosion-resistant metal, to dispense entirely with the anchor rod and rod connections in certain installations.

There has been shown according to present preference, an anchor of so-called three-way type, characterized by three blades or vanes whose median lines are disposed at angles of 120 degrees to each other. It will be seen that this arrangement of blades and body lends itself particularly to an anchor utilizing a type of blade, the heel portion of which is of substantial width, the three-blade arrangement also providing an augmented area of blade engagement against the overlying earth, a large part of which area is close to the anchor body. The three-blade arrangement thus enables the use of shorter blades or vanes than would be required were four blades employed, when all are disposed in a common plane. The blades may likewise be shorter than were only two thereof provided to afford the requisite area of engagement. Obviously the body of an

anchor of this type may be considerably shorter, and require less metal, than is the case wherein say four blades are employed and arranged in pairs in superposed planes.

Proceeding now to a description of the novel type of blade or vane, these are preferably, in the example shown, of broad shovel-shape, the earth-engaging surface of which lies substantially in a plane from the heel of the blade outwardly to the zone designated generally at 32 (Fig. 4), wherein the margins of the blade start to converge toward the point 33 thereof. Between the zone 32 and the tip 33, the blade bends outwardly or downwardly according to the plane of reference, and further by preference is beveled at its outer end (Fig. 4) as to present a sharpened entering edge. This offers the advantage in attaining a quick and positive initial engagement of the tip portion of each of the blades with the surrounding earth, after the anchor is driven to its maximum extent. Thereafter a short upward pull on the anchor serves definitely to expand the blades, i. e. to move them downwardly about their pivots to the horizontal position shown by Fig. 7. The rear portion or heel part, nearest the body of the anchor of each of the blades, is characterized by a central reinforcing rib or strut 35 (Figs. 6 and 7). This element increases in depth toward the heel of the blade, and its rear extremity 36 forms a planar surface abutting a seat 37 therefor on the upper margin of the pilot or point 10 of the anchor. Two additional struts or ribs 38 (Fig. 2) are formed, one on each side of the rib 35, the ribs 38 being of tapered width and terminating inwardly in the apertured ears 39, the pivot-receiving openings of which are indicated at 40.

Experience and numerous breaking experiments have indicated that the zone in which occurs the greatest tendency to breakage, lies in the rear portion of the vane or blade, and in or adjacent its pivot structure. According to the present preferred design, the blade has been materially strengthened in this zone through the provision of the ribs 35 and 38, and the resulting thickened blade section just outwardly of the projections or ears 39. The usual zone of weakness has also been materially strengthened and improved in design through the provision of the mating abutments 36 and 37, serving to distribute the otherwise extremely high unit pressures in the areas of engagement of the blades with the body. This provision tends materially to prevent any spalling tendency, as might otherwise be noted when the blades and body are formed of cast metal.

The somewhat modified form of anchor shown by Fig. 9 may be in all important respects similar to the structure shown by Figs. 1 through 8, the reference numerals applied to the elements of the anchor of Fig. 9 designating parts corresponding to those heretofore described, except bearing the letter suffix A in designating the elements of Fig. 9. An exception is, however, noted in the provision of a central recess or bore 45 which extends axially of the anchor body to a much greater depth than that shown by Fig. 4. The socket 45 is shown as 65 terminating in the pilot portion 10A, particularly in a transverse passage or socket 46 extending from one side of the pilot inwardly a sufficient depth to accommodate a rod nut 47. The passage 46 is preferably rectangular or otherwise shaped 70 in transverse section so that when the nut is inserted therein, the anchor rod may be threaded into the nut 47 without any tendency toward rotation of the nut in the body. It will be noted this arrangement effects a substantial saving in 75

weight of metal required for the anchor body. In case the anchor is formed, as preferred, of malleable castings, the increased depth of rod socket and the reduction in weight of metal by reason 5 of the passage 46, preferably formed by coring, does not materially reduce the different sections of the anchor required to resist the greatest stresses, in fact the strength of the unit section of metal is desirably enhanced in certain zones, 10 due to decreased thicknesses and better annealing penetration.

The manner of setting and use of an anchor of the type described, conforms in a general way to the practice and function of expanding anchors 15 of older types; it may however be noted that the usual practice is to provide a prebored earth opening, corresponding approximately in length to the desired depth or location of the anchor below the surface of the ground, the axis of the opening 20 conforming also to the axis of the tension element such as the cable or rod. The anchor is driven into place by an impact or pressure implement engaging a tube or special driving tool, which in turn engages the projections 18 of the anchor body. When the anchor has attained the desired depth, a short upward pull on the tension 25 element causes the tips of the vanes to engage the surrounding soil, and to become expanded to assume its permanent relation to the surrounding 30 earth, ready for attachment of the guy cable or the like to the pole or other object to be anchored.

It will be seen that anchors of the types exemplified by the foregoing description, will fully attain each of the several objects heretofore expressed and implied; that they may be manufactured economically, since they require but a minimum weight of metal, and that the improved type described offers a distinct advance in anchors of expanding type, due to the special elements of design and most advantageous use of metal in the zones subjected to the greater stresses.

While the invention has been described by making a somewhat specific reference to a presently preferred embodiment, the description is not to be construed in a limiting sense, since many changes may be made in the elements of the device, as well as in their combinations and arrangements, without departing from the full 50 intended scope of the invention as defined by the claims hereunto appended.

I claim:

1. In an earth anchor of expanding type, a body, spaced arms formed integrally with and extending laterally of said body, a plurality of blades or vanes pivotally carried by said arms, a pilot portion depending from said body and formed integrally therewith and with said arms, the pilot portion being formed with projections 55 each diverging from the point of the pilot to the zone of one of the blades, said projections each being of a width near the blade, in excess of the width of the blade pivot portion and the length of the blade pivot, and adapted to deflect foreign objects, in setting the anchor, to zones laterally of said pivot portion.

2. In an earth anchor of expanding type, a body, a pilot portion on the body characterized by projections and channels of relatively divergent trend from the point of the pilot to a zone substantially upwardly thereof, a plurality of blade pivot seats formed integrally with, and extending laterally of the body, above the pilot portion, said pivot seats also being formed integrally with the upper end of said pilot portion, 70 and disposed radially inwardly of the widest portions of the pilot projections, a body extension above the pivot seats, blades carried by said pivot seats, and a plurality of lateral projections on said upwardly extending portion, each adapted as a stop for the adjacent blade, overlying the pivot structure thereof, and so formed and located as to limit the blade-retracting movement to substantially a vertical position.

a body extension above the pivot seats, blades carried by said pivot seats, and a plurality of lateral projections on said upwardly extending portion, each adapted as a stop for the adjacent blade, and so formed and located as to limit its 5 retracting movement to substantially a vertical position.

3. An earth anchor of expanding type including a body portion and a pilot portion formed integrally therewith and extending therebeyond, 10 each of said portions being characterized in section by three lateral projections or arms, with the arms of the body portion arranged in superposed registry with the pilot arms, and connected thereto, the arms of the body portion being apertured for the pivotal securement of the blades, a blade pivotally secured near its inner end or heel, to each of said body arms, and the arms of the pilot portion serving to define earth-engaging, anti-spiralling channels therebetween, 20 the inner portions of the pilot arms underlying the body arms, each being of a lateral width in excess of that of its adjacent body arm and the heel portion of the blade pivoted thereto, whereby in setting the anchor, said inner portions of 25 the pilot arms serve to deflect foreign objects to zones laterally of the body arms and heel portions of the blades.

4. In an anchor of expanding type, a body, spaced arms formed integrally with and extending laterally of said body, a plurality of blades or vanes pivotally carried by said arms, a pilot portion depending from said body and formed integrally therewith and with said arms, the pilot portion and body being characterized by an 30 undercut or recessed part in which are located the pivotal connections between the body and blades, the pilot portion being formed with projections below said undercut part, and each diverging from the point of the pilot to the undercut or recessed part, said projections each being of a width near the blade, in excess of the width of the blade pivot portion and the length of the blade pivot, and adapted to deflect foreign objects, in setting the anchor, to zones laterally of 35 and outwardly beyond said pivot portion.

5. In an earth anchor of expanding type, a body, a pilot portion on the body characterized by projections and channels of relatively divergent trend from the point of the pilot to a zone 50 substantially upwardly thereof, a plurality of blade pivot seats formed integrally with, and extending laterally of the body, above the pilot portion, said pivot seats also being formed integrally with the upper end of said pilot portion, 55 and disposed radially inwardly of the widest portions of the pilot projections, a body extension above the pivot seats, blades carried by said pivot seats, and a plurality of lateral projections on said upwardly extending portion, each adapted 60 as a stop for the adjacent blade, overlying the pivot structure thereof, and so formed and located as to limit the blade-retracting movement to substantially a vertical position.

6. An earth anchor of expanding type including a body portion and a pilot portion formed integrally therewith and extending therebeyond, each of said portions being characterized in section by three lateral projections or arms, with the arms of the body portion arranged in superposed registry with the pilot arms and connected thereto, the arms of the body portion terminating within the confines of the uppermost portions of the pilot arms so as to be radially recessed relative thereto, and the body arms being 70 75

5 apertured for the pivotal securement of the blades, a blade pivotally secured near its inner end or heel, to each of said body arms, and the arms of the pilot portion serving to define earth-engaging, anti-spiralling channels therebetween, the inner portions of the pilot arms underlying the body arms, each being of a lateral width in

excess of that of its adjacent body arm and the heel portion of the blade pivoted thereto, whereby in setting the anchor, said inner portions of the pilot arms serve to deflect foreign objects to zones laterally and radially outwardly of the body arms and heel portions of the blades. ⁵
